UNITED STATES PATENT OFFICE.

GEORGE E. NORRIS; OF COLUMBUS, OHIO, ASSIGNOR TO COLUMBUS ASEPTIC FURNITURE COMPANY, OF COLUMBUS, OHIO, A FIRM.

GLASS SUPPORTING AND CONNECTING DEVICE.

No. 861,311.

Specification of Letters Patent. Patented July 30, 1907.

Application filed June 11, 1906. Serial No. 321,108.

To all whom it may concern:

Be it known that I, GEORGE E. NORRIS, a citizen of the United States, residing at Columbus, in the county of Franklin and State of Ohio, have invented certain new and useful Improvements in Glass Supporting and Connecting Devices, of which the following is a specification.

My invention relates to a glass supporting and connecting device and has for its object the provision of a hollow standard adapted to form a corner post for show cases, or show windows, the glass plates forming said show cases or windows lying at an angle to each other and being supported at their adjacent edges only by the clamp forming the subject matter of the present invention.

A further object of the invention is the provision of a supporting post having outwardly flaring sheet metal wings which extend the full length of the glass to be supported and a clamp adapted to be drawn toward said post, said clamp also having wings which extend the full length of the glass to be supported, the wings of the post and the wings of the clamp being adapted to be bent to support the glass at any desired angle.

Further objects and advantages of the invention will be set forth in the detailed description which now follows:

In the accompanying drawing: Figure 1 is a horizontal section of a clamp and support embodying the present invention, illustrating two glass panes clamped therein, said panes being broken away, and, Fig. 2 is an elevation of the inner side of said clamp.

Like numerals designate corresponding parts in both of the figures of the drawing.

Referring to the drawing, the numeral 5 designates a tube. This tube has secured thereto a shell 6. This shell may be secured to the tube 5 by pins, screws, or by brazing. This latter method has been illustrated in the present instance. As is best illustrated in Fig. 1, the contact of the shell 6 with the tube 5 terminates as

at 7, said shell having outwardly flaring wings 8. A clamp 9 comprises a substantially U-shaped portion 10, outwardly flaring portions 11, and wings 12, said wings lying substantially parallel to the wings 8. Strips of fabric, and preferably strips of felt 13, are inserted between the wings 8 and the glass and strips of fabric 14 are inserted between the wings 12 and the glass. A screw 15 passes through the U-shaped portion of the clamp 9 and is threaded into the tube 5. When this screw is screwed into said tube, it is apparent that the clamp 9 will be drawn toward said tube, thereby forcing the wings 12 into contact with the strips of felt 14

and forcing the glass panes 16 which lie between the fabric strips 14 and 13 firmly against said latter strips, which are in turn forced against the wings 8. It will be apparent that this action results in binding the glass panes 16 firmly together.

The U-shaped portion 10 of the clamp 9 is adapted to support shelves when desired. A key-hole slot 17 is formed in this U-shaped portion 10 of the clamp 9 as is illustrated in Fig. 2 of the drawing, said key-hole slot 17 permitting the insertion therein of members carried by the shelves which are not shown.

It is apparent that the tube 5 and the shell 6 when brazed together, form practically one piece of metal and it is not absolutely necessary to form these parts in two pieces, though that is the cheapest and most convenient way of manufacturing the device. The outward ears 8 might be carried directly by the tube 5 and it is to be understood that the present invention includes such a construction.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

By forming the wings 8 and the wings 12 of sheet metal, it is possible to bend these wings to varying angles. In the drawing illustrated, the panes of glass 16 are shown supported substantially at right angles to each other. It is often desirable, however, to support these panes at other than right angles and with the construction shown, this may be accomplished by bending the wings 8 and 12 to varying angles. This result may be accomplished, while means are still provided for supporting the glass throughout its height.

What I claim, is:

In a device of the character described, the combination with a hollow metallic supporting post, of a pair of flexible wings carried by said supporting post and extending substantially the full length of the glass to be supported, a clamp, means for drawing said clamp toward the post, and flexible wings forming a part of said clamp and extending substantially the full length of the glass to be supported.

In testimony whereof I affix my signature in presence of two witnesses.

GEORGE E. NORRIS.
